Primary Examiner — Adir Aronovich(74) *Attorney, Agent, or Firm* — Klarquist Sparkman, LLP(57) **CLAIM**

We claim the ornamental design for a camera housing, as shown and described.

DESCRIPTION

FIG. 1 is a a top perspective view of the camera housing; FIG. 2 is a front elevation view of the camera housing of FIG. 1;

FIG. 3 a top plan view of the camera housing of FIG. 1; FIG. 4 is a bottom plan view of the camera housing of FIG. 1; FIG. 5 is a right side elevation view of the camera housing of FIG. 1;

FIG. 6 is a left side elevation view of the camera housing of FIG. 1;

FIG. 7 is a rear elevation view of the camera housing of FIG. 1; and,

FIG. 8 is a bottom perspective view of the camera housing of FIG. 1.

The broken lines in the drawings depict portions of the camera housing in which the design is embodied and form no part of the claimed design.
